UNITED STATES PATENT OFFICE.

ROBERT M. BOODY, OF HAVERHILL, MASSACHUSETTS, ASSIGNOR TO LOUIS M. BOODY, OF HYANNIS, MASSACHUSETTS.

FIRE-ESCAPE.

SPECIFICATION forming part of Letters Patent No. 654,705, dated July 31, 1900.

Application filed May 3, 1900. Serial No. 16,342. (No model.)

To all whom it may concern:

Be it known that I, ROBERT M. BOODY, a citizen of the United States, and a resident of Haverhill, in the county of Essex and State 5 of Massachusetts, have invented certain new and useful Improvements in Fire-Escapes, of which the following is a specification.

This invention relates to an improved means for lowering a person from a window 10 in a building in case of fire, which is adapted to lower the person at a certain speed, which will not be varied whether the person is heavy or light.

For an understanding of my invention attention is called to the accompanying drawings, in which—

Figure 1 is a central cross-section on the line X X of Fig. 2. Fig. 2 is a front elevation with the casing removed. Fig. 3 is a detail view of the part which includes the clutch. Figs. 4 and 5 are side and end views of a noose which I use in this connection.

The whole device is inclosed in a casing A, and the various parts are journaled or supported in strips of metal B, which are connected in various ways to the casing. A central shaft C is fixed in the casing and extends from side to side thereof. A sleeve c is journaled on said shaft and is provided with a gear c' at one end and a series of clutch-teeth c² at the other. A gear c³ is also journaled on said shaft and is provided with a boss having teeth c⁴, which correspond with the teeth c² of the sleeve c. An escapement-wheel D, having a small gear d on the rear side thereof, is journaled on a fixed shaft d', the gear d being in mesh with the gear c³. A pallet d² is journaled on a fixed shaft d³, said pallet being arranged so that it engages the teeth of the escapement-wheel in the usual manner. The teeth of the escapement-wheel are made straight on one side and curved on the other, as shown in Fig. 2, and the teeth of the pallet are made V-shaped, as shown. By providing a straight face on one side of the teeth of the wheel the pallet will come firmly into engagement, so that there is no possibility of slipping, yet the curved surface on the other side of the teeth aids materially in throwing out the tooth of the pallet as the direction of motion is changed. Integrally connected

with the pallet d² is an arm d⁴, which is provided with a circular-shaped end d⁵. A regulator d⁶ is journaled on the shaft c and is provided with a notch d⁷ in its lower end, with 55 which the end d⁵ of arm d⁴ engages, and on its upper end it is provided with an arc-shaped weight d⁸. This arc-shaped weight d⁸ is provided with a notch d⁹ on its outer surface, said notch extending nearly the entire 60 length thereof, two projections or shoulders being thereby formed on the weight at each end of the notch. A flat spring d¹⁰ is firmly secured to the casing in any convenient way and depends so that its lower end is adapted 65 to engage the ends of the notch d⁹. The sleeve c has two guiding-flanges E secured thereto, and a suitable tape or steel band e is suitably secured to said sleeve between said flanges, so that said sleeve constitutes a wind- 70 ing-drum about which the tape will be wound when the sleeve is rotated. The inner end of the band e is secured to sleeve c in any suitable manner. The end of the band is provided with a ring e², and a hook e' is adapted 75 to slide on the band and be connected to the ring e², so as to form a noose which may be passed around the body of the person using the device.

The sleeve c is capable of a sliding movement on the shaft C and is forced against the gear c³ by the spring F, which is confined between the collar c⁵ on the sleeve c and a ring b, which is secured in one of the supports B. A large gear G is journaled in the frame and 85 in one of the supports B, and a crank g is adapted to be connected thereto.

The whole device may be secured in a room in any convenient way. For example, strips of metal or other suitable material b' may be 90 connected to the casing at one end, as indicated in Fig. 1, and their opposite ends may be tied or connected in any suitable manner by a hook or buckle. These strips will be passed about or secured to any suitable object 95 in the room, as will be readily understood.

The operation is as follows: Assuming that the tape e is wound around the sleeve c and that the machine is suitably secured at some place in the room from which the person is 100 to be lowered, the noose (shown in Figs. 4 and 5) is slipped around the body of the person,

and as his weight is thrown onto the band e the band will be unwound and the sleeve c will be rotated. The teeth of the clutch c^2 will be in engagement with and will rotate the gear c^3 . This gear c^3 will in turn rotate the gear d and the escapement-wheel D , which is formed integrally therewith. The pallet d^2 will engage the teeth of the escapement-wheel and will be thrown back and forth in the usual manner, liberating one tooth of the wheel at a time and preventing it from rotating beyond a certain speed. As the pallet is tipped from one side to the other it will swing the arm d^4 , which in turn will oscillate the regulator d^6 , and as the regulator reaches almost the end of its stroke in either direction the end of the spring d^{10} will engage one of the projections at the end of the notch, so that the latter part of the movement of the regulator will be retarded. The spring will then give the regulator an impulse in the opposite direction. This impulse will occur at the end of each oscillation and will absolutely prevent any failure to swing on the part of the pallet, so that the motion thereof back and forth will be positive, and the danger of the pallet becoming locked with the escapement-wheel, so that the latter will not turn, will be reduced to a minimum. The regulator will not, however, increase the speed of the escapement-wheel, but will regulate the movement of the pallet, so that the speed of the escapement-wheel will be regular. It will be noted that when the head d^8 of the regulator is thrown on one side of the vertical line through its axis the pallet will be thrown on the other side of the same vertical line. In this way one acts as a counterbalance for the other. When the person has been lowered to the ground, the tape or band may be wound up again by turning the large gear G by the crank g . When this is done, the sleeve c will slide back, so that the teeth of the clutch will

disengage and the gear c^3 will not be rotated. In this way the pallet will not interfere with or retard the winding up of the tape, so that this operation may be quickly performed.

If one person only is to be lowered, the end of the tape may be secured in the room and the apparatus to the person in any convenient way, so that it will be lowered with the person.

Having described my invention, what I claim as new, and desire to secure by Letters Patent of the United States, is as follows:

1. A device for the purpose described comprising a winding-drum, a tape which is adapted to be wound therearound, an escapement-wheel which is connected therewith, a pallet which is adapted to engage said wheel, an arm extending from said pallet, a pivoted lever having one end connected to said arm and having its opposite end weighted, and a spring which is adapted to engage said lever as it approaches the limit of its movement in each direction.

2. A device for the purpose described comprising a winding-drum, a tape which is adapted to be wound therearound, an escapement-wheel which is connected therewith, a pallet which is adapted to engage said wheel, an arm extending from said pallet, a pivoted lever having one end connected to said arm and having its opposite end provided with a weight which extends from opposite sides of said lever, projections which extend from said weight near each end thereof, and a spring which is adapted to engage one of said projections as said lever approaches the limit of its movement in each direction.

In testimony whereof I have affixed my signature in presence of two witnesses.

ROBERT M. BOODY.
